UNITED STATES PATENT OFFICE

2,482,033

ELECTROMAGNETICALLY ACTUATED
VIBRATOR

Henry J. Sevigny, Methuen, Mass.

Application April 3, 1947, Serial No. 739,193

3 Claims. (Cl. 172—126)

1

This invention relates to a radio set testing device.

It is an object of the present invention to provide a testing device or probe which will vibrate when applied to the radio parts such as tubes, condensers, resistors and transformers, will produce a noise in the speaker of the radio set if any of the parts are defective as a result of poor soldering connections or loose elements within the parts.

Other objects of the present invention are to provide a radio set testing device, which is of simple construction, easy to handle and operate, inexpensive to manufacture and efficient in operation.

For other objects and for a better understanding of the invention, reference may be had to the following detailed description taken in connection with the accompanying drawing, in which

Fig. 1 is a side elevational view of my radio set testing device.

Fig. 2 is a longitudinal cross-sectional view of the testing device showing the internal parts thereof.

Fig. 3 is an end elevational view of the testing device looking upon the Lucite probing end.

Fig. 4 is a transverse cross-sectional view taken on line 4—4 of Fig. 2.

Fig. 5 is a transverse cross-sectional view taken on line 5—5 of Fig. 2.

Referring now to the figures, 10 represents a cylindrical hollow casing having an annular shoulder formation 11 against which there is extended a solenoid having wires 13 extending from its upper end and outwardly through an end member 15 on the end of the casing. Within the solenoid is a core 16 having a recess 17 with a coil spring 18 therein adapted to engage with an armature 19 made of soft iron and having rings 21 extending around its forward end. Connected to the armature is a Lucite rod 22 which extends through a sleeve 23 with a tapered exterior surface 24. The connection of the rod 22 with the soft iron armature 19 is effected by means of a threaded rod 25 threaded into both the core 16 and the Lucite rod 22. Surrounding the Lucite adjacent to the armature 19 is a rubber sleeve or bumper 26. The spring 18 urges the armature 19 away from the end of the core 16. When alternating current is applied to the wires 13, the armature 19 will vibrate so as to knock upon the parts of the radio which the testing device is applied to. The Lucite 22 being of soft material none of the parts with which the testing device engages will be burred.

2

While various changes can be made in the detail construction, it shall be understood that such changes shall be within the spirit and scope of the present invention as defined by the appended claims.

I claim:

1. In a radio set testing device, a hollow casing provided with an annular shoulder intermediate its ends, a solenoid adapted to be connected to a source of electrical energy positioned within said casing and having one end abutting said shoulder, a core disposed longitudinally within said solenoid, there being a recess extending inwardly from one end of said core for a portion of its length, an armature arranged contiguous to the recessed end of said core and mounted for movement toward and away from the latter, resilient means seated in said recess and operatively connected to one end of said core and said armature for normally biasing the latter apart, a sleeve spaced from said armature and closing an end of said casing, a Lucite rod operatively connected to said armature and projecting through said sleeve, and resilient means interposed between said armature and sleeve for limiting the movement of said armature away from said core.

2. In a radio set testing device, a hollow casing provided with an annular shoulder intermediate its ends, a solenoid adapted to be connected to a source of electrical energy positioned within said casing and having one end abutting said shoulder, a core disposed longitudinally within said solenoid, there being a recess extending inwardly from one end of said core for a portion of its length, an armature arranged contiguous to the recessed end of said core and mounted for movement toward and away from the latter, resilient means embodying a coil spring seated in said recess and operatively connected to one end of said core and said armature for normally biasing the latter apart, a sleeve spaced from said armature and closing an end of said casing, a Lucite rod operatively connected to said armature and projecting through said sleeve, and resilient means embodying a rubber bumper circumscribed about said rod and interposed between said armature and sleeve for limiting the movement of said armature away from said core.

3. In a radio set testing device, a hollow casing provided with an annular shoulder intermediate its ends, a solenoid adapted to be connected to a source of electrical energy positioned within said casing and having one end abutting said shoulder, a core disposed longitudinally within said solenoid, an armature arranged contiguous to said

core and mounted for movement towards and away from the latter, resilient means operatively connected to one end of said core and said armature for normally biasing the latter apart, a sleeve spaced from said armature and closing an end of said casing, a Lucite rod operatively connected to said armature and projecting through said sleeve, and resilient means interposed between said armature and sleeve for limiting the movement of said armature away from said core.

HENRY J. SEVIGNY.
